US00D563249S

(12) **United States Design Patent** (10) Patent No.: **US D563,249 S**
Chen (45) Date of Patent: **** Mar. 4, 2008**

(54) **SCAN TOOL**

(75) Inventor: **Ion Chen**, Laguna Hills, CA (US)

(73) Assignee: **Innova Electronics Corporation**,
Fountain Valley, CA (US)

(**) Term: **14 Years**

(21) Appl. No.: **29/271,222**

(22) Filed: **Jan. 12, 2007**

(51) **LOC (8) Cl. 10-04**

(52) **U.S. Cl. D10/78**

(58) **Field of Classification Search** D10/78;
324/76.12, 426; 340/439; 701/24, 29, 33,
701/35; 702/57

See application file for complete search history.

(57) **CLAIM**

The ornamental design for a scan tool, as shown and
described.

DESCRIPTION

FIG. 1 is a front view of the invention;
FIG. 2 is a rear view of the invention;
FIG. 3 is a right side view of the invention;
FIG. 4 is a left side view of the invention;
FIG. 5 is a top view of the invention; and,
FIG. 6 is a bottom view of the invention.
